HOTDOG ROASTER

Joseph Di Pirro, 122 Freund St., Buffalo, N.Y. 14215

Filed Nov. 24, 1972, Ser. No. 308,933

Term of patent 7 years

Int. Cl. D7—02

U.S. CL. D7—95

FIG. 1 is a side elevational view of a hotdog roaster showing my new design with an intermediate portion of the handle being removed for convenience of illustration;

FIG. 2 is a top plan view of FIG. 1;

FIG. 3 is a fragmentary bottom plan view taken substantially on the plane of line 3—3 of FIG. 1;

FIG. 4 is an end elevational view looking from left to right at FIG. 1;

FIG. 5 is an end elevational view looking from right to left at FIG. 1;

FIG. 6 is a side elevational view of the hotdog roaster of FIG. 1 showing a modification thereof with an intermediate portion of the handle being removed for convenience of illustration;

FIG. 7 is a top plan view of FIG. 6;

FIG. 8 is a fragmentary bottom plan view taken substantially on the plane of line 8—8 of FIG. 1;

FIG. 9 is an end elevational view looking from left to right at FIG. 1; and

FIG. 10 is an end elevational view looking from right to left at FIG. 1.

I claim:

The ornamental design for a hotdog roaster, as shown and described.
